UNITED STATES PATENT OFFICE.

ALEXANDER T. GIBSON, OF OAKLAND, CALIFORNIA.

CLAMP FOR WINDOW LOCKS.

Application filed June 20, 1923. Serial No. 646,670.

To all whom it may concern:

Be it known that I, ALEXANDER T. GIBSON, a citizen of the United States, and a resident of Oakland, county of Alameda, State of California, have invented a new and useful Clamp for Window Locks, of which the following is a specification.

The present invention relates to improvements in window locks and has particular reference to a means for holding the two sashes of a window in spaced relation so that the window may be opened for ventilating purposes without allowing a person to increase the opening for the purpose of entering through the window. The device disclosed in the present application is an improvement on the window lock described in my co-pending application Serial No. 625,393, and the main improvement consists in the construction of certain clamps used in the window lock. The principal advantages of these clamps will appear as the specification proceeds.

The preferred form of the invention is illustrated in the accompanying drawing in which Figure 1 shows a front view of my device as attached to the two sashes of a window, Figure 2 a side view of the same as viewed from line 2-2 of Figure 1, Figure 3 a sectional detail view of two cooperating elements of my clamp, Figure 4 a cross-section taken along line 4-4 of Figure 3, Figure 5 a detail view in front elevation of a combination handle and wrench, Figure 6 a vertical section through the same taken along line 6-6 of Figure 5, Figure 7 a detail view of a portion of a handle forming part of the means for connecting the two clamps and for handling the same in spaced relation and Figure 8 a vertical section through the same. While I have shown only the preferred form of my invention I wish it to be understood that various changes and modifications may be made within the scope of the claims here-to attached without departing from the spirit of the invention.

My window lock consists in its principal features of two clamps (1) and (2) and the means (3) for holding the same in spaced relation. The two clamps are preferably secured to the top members (4) and (6) of the two sashes (7) and (8) and their construction is shown in detail in Figures 3 and 4. Each clamp comprises an internally threaded elongated member (9) hav-

ing a lip (11) extending from its bottom at right angles to the threaded portion. The latter portion is shaped to form a saddle or seat for a shoe (12) adapted to ride on the saddle. The shoe is provided with a lip (13) extending at right angles thereto in registering relation to the lip (11). The engagement between the shoe and the saddle is such that the shoe is held against rotary motion on the saddle as shown in Figure 4 but may ride on the same, the latter motion being limited only by the length of the engaging members and by a small projection (4) on the saddle (9). The shoe has a perforation (16) which is aligned with the threaded perforation (17) in the saddle member so that a bolt (18) may be introduced through the perforation (16) to engage the threads (17) and to force the two lips (11) and (13) upon the frame member (14) of the upper sash. It should be noted that the lips are formed with slanting outer faces which prevents force from being applied from the outside for the purpose of removing the clamp and that the outer lip (11) is provided with an internal rib (19) adapted to dig into the yielding material of the window frame so as to prevent the clamp member (11) from being pushed upwardly by an intruder. The bolt (18) of the upper clamp may be rotated by means of a handle (21) constituting one link of the spacing means (3). The handle is formed as shown in Figures 7 and 8 to slip over the bolt and is recessed as shown at (22) to engage the head of the bolt so that when the handle is engaged with the head a simple revolving motion of the handle will tighten the bolt. For the lower clamping member I preferably use the handle illustrated in Figures 5 and 6 comprising a hub (23) having a plurality of arms (24) extending therefrom in radial direction and provided with the recess (26) adapted to engage the head (27) of the bolt (28) used for the lower clamp. Each arm is provided with the perforation (29). The connecting means (3) includes a plurality of links (31) of different lengths joined by means of couplings (32) and terminates in an end member (34) having an eye therein which may be made to register with any one of the perforations (29) in the arms (24) of the lower handle. The member (34) may be locked to the lower handle by a padlock (36) or any other suit-

able locking means. It will be readily seen that this arrangement allows of a close adjustment of the clamp since if the handle shown in Figure 5 is used the latter may 5 be locked at each one-sixth of a turn.

The operation of the device will be readily understood from the foregoing description. First, the upper clamp (1) is secured to the upper frame member of the 10 upper sash by means of the handle (21) which latter is adjusted upon the head of the bolt (18) in such a manner that it assumes a vertical position when the clamp is tight on the frame member of the upper 15 sash. Next, the clamp (2) is secured upon the upper frame member of the lower sash in a similar manner. Links (31) are added by means of couplings (32) to produce a desired length of connecting means 20 and the eye of the end member (34) is brought in registry with one of the perforations (29) of the lower handle and locked to the latter by means of the padlock (36) or whatever means is desired to be used 25 for this purpose. It is now impossible for anybody from the outside to increase the opening of the window without breaking the lock or any of the other members of the locking device.

30 It is understood of course, that the particular clamp described in this specification is not confined to be used with a window lock and protection is sought on the clamp as such as an article of general adaptation.

35 I claim:

1. A clamp of the character described, comprising an elongated seat having a flat bottom, a lip extending from one end thereof at right angles to the bottom, and being 40 of uniform cross-section except for the lip and formed with an axial threaded bore, a

shoe adapted to ride on the seat and formed to completely encircle the top and the sides thereof cross-sectionally, a lip extending from one end of the shoe in juxtaposition to the lip of the shoe, and a bolt adapted to be guided through a perforation in the shoe into threaded engagement with the seat for tightening the lips upon an object. 45

50 2. A clamp of the character described, comprising an elongated seat having a flat bottom, a lip extending from one end thereof at right angles to the bottom, and being of uniform cross-section except for the lip and formed with an axial threaded bore, a shoe adapted to ride on the seat and formed to completely encircle the top and the sides thereof cross-sectionally, a lip extending from one end of the shoe in juxtaposition to the lip of the shoe, and a bolt adapted to be guided through a perforation in the shoe into threaded engagement with the seat for tightening the lips upon an object with a handle loose upon the bolt having a recess 55 therein adapted to fit on the inner edge of the bolt head for rotating the latter.

60 3. A clamp of the character described, comprising an elongated saddle-shaped seat having a lip extending from one end thereof, a shoe adapted to ride on the seat having a lip extending from the opposite end thereof and a bolt passing through the shoe and threadedly engaging the seat for clamping the lips upon an object, with a handle 65 loose upon the bolt having a recess therein adapted to fit on the bolt head for rotating the latter, and having a plurality of radial arms allowing the handle to be locked in any one of various positions. 70

ALEXANDER T. GIBSON.
